WIRE TIGHTENER

Burt J. Bradley, Boise, Idaho

Application April 29, 1946, Serial No. 665,873

5 Claims. (Cl. 140—119)

1

The present invention relates to improvements in wire tighteners, and has particular reference to a tightener adapted for use in connection with concrete forms.

Concrete forms are usually constructed of boards arranged in spaced and parallel relation to form a channel for receiving the concrete, stakes supporting the boards from the outside, spanning members between the boards and tie wires for drawing the boards toward the spacing members. The tie wires should be strong and well stretched to prevent the form from bulging outward under the weight of the freshly poured concrete.

In the present invention it is proposed to provide a convenient means for tightening the wire upon the form, that is particularly effective in tensioning the wire throughout the length thereof.

A wire may be tightened about an object by twisting the ends of the wire, and it also may be tightened by exerting direct pull on the ends of the wire.

In the present invention I propose to provide a wire tightener that will combine the two effects and will, in a single action, exercise lengthwise pull on the wire and twist the ends of the wire about one another, either at the same time or in related order.

A mere twisting of the ends of the wire may be confined to a more or less local effect, whereas direct pull exerted on the ends of the wire will effectively tension the wire throughout the length thereof.

Thus, by combining the two effects, it is proposed to provide a wire tightener that will take up the slack throughout the full length of the wire, and at the same time and in the same action, will twist the ends of the wire about one another to firmly hold the wire in tensioned condition.

Further objects and advantages of my invention will be disclosed as the specification continues, and the new and useful features of the same will be fully defined in the claims hereto attached.

The preferred forms of my invention are illustrated in the accompanying drawing forming part of this application, in which:

Figure 1 shows a perspective view of a concrete form having my wire tightener applied thereto;

Figure 2, a horizontal section through the device, with a slight modification;

Figure 3, a perspective detail view of a screw head used in my invention;

Figure 4, a sectional detail view taken along line 4—4 of Figure 2; and

Figure 5, a view similar to that of Figure 2, but showing a modified form of the invention.

While I have shown only the preferred forms of my invention, I wish to have it understood that various changes or modifications may be made within the scope of the claims hereto attached.

2

without departing from the spirit of the invention.

Referring to the drawing in detail, Figure 1 shows the conventional set-up of a concrete form as comprising a pair of boards 1 set on edge in spaced and parallel relation, a series of stakes 2 on opposite sides of the boards for giving lateral support to the same, and spacers 3 interposed between the boards.

The stakes are arranged in opposing pairs, and the spacers are preferably alined with the stakes.

The wire 4, which is cut to the proper length, is guided about the stakes in the manner shown. The central portion is placed about one stake, and the end portions are passed through holes 5 in one of the boards and are then made to cross between the boards and are passed through corresponding holes 6 in the other board, to emerge from the latter adjacent opposite sides of the second stake to present loose ends following the sides of the latter stake and projecting beyond the outer edge thereof.

My wire tightener comprises in the form shown in Figure 1, a yoke 7 and a screw 8 threaded through the top thereof.

25 The yoke 7 may be made in any suitable form and is here shown as a strap of metal bent into semi-cylindrical shape and having two radial flanges 9 adapted to bear against the edge of the stake, the flanges being preferably formed with 30 pointed prongs 10 adapted to anchor in the stake material.

35 The screw 8 extends through the yoke perpendicularly to the stake and is threaded, in the form shown in Figure 1, through a hub 11 secured upon the yoke, the outer end of the screw having a suitable handle 12. The inner end of the screw terminates in a square head facing the stake and adapted to have the ends of the wire anchored thereto.

40 The details of the head are illustrated in Figures 2, 3 and 4, from which it appears that the head is in the form of a fairly heavy, substantially square block having its outer face 13 arranged opposite the stake and having two grooves 14 therein, the grooves extending from the center in opposite directions and having inclined bottoms so as to gain in depth toward the edges of the block. The grooves are adapted to receive the two projecting ends of the wire after the latter have 45 been crossed over the near face of the stake.

50 Two additional grooves 15 are cut into the block vertically from the upper edge to intersect the first pair of grooves at their outer ends and these grooves have cams 16 mounted thereon on pivots 17, each cam comprising a handle 18 projecting normally above the block in substantially vertical position and a cam section 19 normally clearing the wire disposed in the lower groove, but adapted to be clamped upon the same 55 60 when the handle is thrust outward.

The wire-engaging face of the cam is preferably serrated for a better grip upon the wire, as shown. The two grooves 15 are arranged at a slight forward angle with respect to the rear face 13, so as to allow the operator to clamp the cams down on the wires with a slight forward pull, that is, away from the form.

The operation of the device thus far described, is as follows:

After crossing the projecting ends of the wire, the operator anchors the yoke to the stake, with the head of the screw facing the wires, guides the two wire ends into the grooves 14 and clamps the same in place by pulling down on the cam handles.

He then turns the screw handle 12 in the proper direction which causes the head 13 to pull away from the stake and to turn at the same time, placing the wire under tension throughout the length thereof and at the same time twisting the wires about one another.

In the form shown in Figure 2, a modified actuating means for the screw is shown. Instead of being threaded into the yoke directly, as in Figure 1, the screw is threaded into a nut 20 bearing on the outer face of the yoke 7 and being revolvable in a bushing 21 secured upon the yoke.

The nut 20 is held against outward movement by a shoulder 22 riding in a registering annular groove in the bushing. The nut is turned by means of a handle 23.

In this form, when the nut is turned in the proper direction, it first exerts outward pull on the head 13 until the entire wire is placed under a certain degree of tension. Thereafter, the resistance to outward pull becomes sufficiently strong to cause the head 13 to revolve with the nut and to thereby twist the ends of the wire about one another.

Due to the fact that the screw and the nut are both revolvable with respect to the bushing 21, endwise motion will substantially cease when rotary motion of the head commences.

In the form shown in Figure 5, a still different effect is obtained:

In this form, the screw 8 is threaded directly into the bushing 24 on the yoke 7, but is revolvable in the head by means of a shoulder 25 riding in a registering recess in the head 26, a retainer and dirt seal being provided at 27. I provide a transverse slot 28 in the screw stem; a transverse pin 29 movable in the slot, and a double Acme thread 30 in the inside of the head, the ends of the pin engaging in the Acme thread.

In this form, the head is preferably formed with a reduced extension 31 to accommodate the length of the Acme thread. The two ends of the wire may be secured upon the head in the same manner as previously described, by suitably modifying the shape of the head, or by means of two holes 32 through which the ends of the wire may be guided for fastening upon the head.

In the above form, with the pin in a midway position, when the screw is turned, the head will first recede with the screw, without turning. In the meantime, the pin 29 will ride in the slot 28 until it reaches one end of the slot. Then relative rotary motion between the head and the screw ceases, and the two turn as a unit to produce a twisting effect.

But, even then the head keeps receding with the screw, so that in this construction, the wire is first tensioned until the pin reaches the end of the slot, while thereafter it is subjected to a combination twisting and tensioning movement. The

degree of initial tensioning movement can be regulated by adjustment of the pin in the slot.

I claim:

1. A tightener for a tie wire having ends straddling a stake and projecting beyond an edge thereof, the tightener comprising a yoke braced against the stake, a head member having means for securing the wire ends thereon and a threaded element co-operable with the yoke in advancing the element, the latter being anchored to the head with limited freedom of revolving motion.

2. In a wire tightener of the character described, a screw head having a groove in its outer face for receiving a wire therein and having a second groove intersecting the first groove and a cam operable in the second groove for anchoring the wire in the first groove.

3. In a wire tightener of the character described, a screw head having two grooves in its outer face extending from a central portion in opposite directions and increasing in depth toward the edges and having a second pair of grooves intersecting the former, the first pair of grooves being adapted to accommodate a pair of intersecting wires therein and the second pair of grooves having cam members operable for locking the wires in the first pair of grooves.

4. A tightener for a tie wire having ends straddling a stake and projecting beyond the edge thereof, the tightener comprising a yoke braced against the stake, a head member having means for securing the wire ends thereon, and threaded means bearing on the yoke for retracting the head, the latter means including a threaded actuating member having a limited freedom of revolving motion with respect to the head so as to cause the latter to retract through a certain distance without turning for tensioning the wire and means for automatically locking the actuating member with respect to the head after a predetermined amount of retraction to cause the head to turn with the actuating member for twisting the wire ends.

5. A tightener for a tie wire having ends straddling a stake and projecting beyond the edge thereof, the tightener comprising a yoke braced against the stake, a head member having means for securing the wire ends thereon, and threaded means bearing on the yoke for retracting the head, the latter means including a threaded actuating member having a limited freedom of revolving motion with respect to the head so as to cause the latter to retract through a certain distance without turning for tensioning the wire and means for automatically locking the actuating member with respect to the head after a predetermined amount of retraction to cause the head to turn with the actuating member for twisting the wire ends, the locking means being operable for adjustment for different distances of the first-mentioned retracting movement.
